UNITED STATES PATENT OFFICE.

WADE H. BABCOCK, OF CLEVELAND, OHIO, ASSIGNOR OF ONE-HALF TO HARRY E. WHITTLE, OF CLEVELAND, OHIO.

ADVERTISING DEVICE.

1,272,184.

Specification of Letters Patent.

Patented July 9, 1918.

Application filed May 5, 1917. Serial No. 166,609.

To all whom it may concern:

Be it known that I, WADE H. BABCOCK, a citizen of the United States, residing at Cleveland, in the county of Cuyahoga and 5 State of Ohio, have invented certain new and useful Improvements in Advertising Devices, of which the following is a specification.

My invention relates to improvements in 10 advertising devices, and more particularly to that class or type in which a series of advertisements are successively shown and illuminated through a window or sight-opening in a stationary casing or housing 15 through the medium of suitable letter or advertisement carrying means together with suitable mechanism for intermittently actuating said letter carrying means.

The primary object of the invention is 20 the provision of a generally improved device of this class which will not only be simple in construction, and efficient in operation, but one in which the letters or words in the various advertisements to be 25 successively displayed and illuminated may be changed at will to meet the varying demands of actual service.

A further object of the invention is the 30 provision of an improved device of this class which will not only successively and automatically display and illuminate the various signs or lettered panels as stopped or held in a stationary position before the 35 sight-opening of the casing, but one in which improved means are provided for successively illuminating or projecting light through the letters of the advertisement in sequential order whereby to spell out the words in the advertisements as successively 40 displayed together with means for cutting out of circuit all of the light projecting lamps just prior to and during the movement of the advertisement carrying drum or device for the display of the next advertisement and the repetition of the spelling out or successive illumination of the letters of the words in the advertisement as 45 above referred to.

A still further object is the provision of 50 improved lamp containing and light projecting compartments arranged to individualize or project the light through the particular letter or device adapted to be brought into registry with such compartments and to be illuminated whereby the let-

ter or device will be clearly defined as distinguished from a successive letter not yet defined by its corresponding individual illuminating means.

With the above mentioned and other ends 60 in view, the invention consists in the novel construction, arrangement, and combination of parts, hereinafter described, illustrated in one of its embodiments in the accompanying drawings, and particularly pointed 65 out in the appended claims.

Referring to the drawings, forming a part of this specification, Figure 1, is an end view, partly in cross section, of an advertising device constructed in accordance 70 with my invention.

Fig. 2, a front elevation of the same, a portion of the front walls of the casing being broken away for the purpose of clearer 75 illustration of the parts.

Fig. 3, a central horizontal sectional view of the same, illustrating in particular the mechanism for energizing and deenergizing the lamps at intervals and actuating and stopping the sign carrying rotary drum in 80 coöperative relation thereto.

Fig. 4, a cross sectional view taken on line 4—4 of Fig. 3.

Fig. 5, a cross sectional view taken on line 5—5 of Fig. 3.

Fig. 6, a cross sectional view taken on line 6—6 of Fig. 3.

Fig. 7, an enlarged detailed view of the intermittently operated spring actuated pinion for intermittently operating the sign 90 carrying rotary drum.

Fig. 8, a cross sectional view of the same taken on line 8—8 of Fig. 7.

Fig. 9, an enlarged detailed view of the pawl or detent mechanism for intermittently releasing and stopping the sign carrying rotary drum in coöperative relation to the continually revolving driving shaft and commutator or lamp flasher mechanism.

Fig. 10, an enlarged side elevation of the 100 same, the drum and commutator shaft being removed for the purpose of clearer illustration of the parts.

Fig. 11, an enlarged detailed view of the motor and motor gearing for actuating the 105 driving shaft and commutator.

Fig. 12, an enlarged view of the intermittently geared end of the driving shaft and commutator.

Similar numerals of reference designate 110

like parts throughout all the figures of the drawings.

The improved advertising device comprises a suitable casing or housing 1, provided at one side with a display or sight-opening 1^a, through which the various signs or advertisements are adapted to be successively displayed by means of the intermittently operated sign carrying device or rotary drum hereinafter referred to. The sight-opening 1^a, is preferably provided with a covering 1^b, of suitable transparent or translucent material, such as glass, or the like.

15 As a means of removably mounting the various parts and the operating mechanism therefor within the casing 1, a removably mounted stationary shaft 2, is mounted within the casing 1, through the medium of 20 end bearings 2^a, in the ends or heads of the casing.

As a means of movably carrying and displaying a suitable series of advertisements or lettered panels successively at the rear 25 of the sight-opening 1^a, a rotary drum is provided, said drum, in the present instance, comprising rotatably mounted heads 3, divided into a series longitudinally extending letter carrying panels by means of longitudinal 30 grooved bars 3^a, and further provided with circumferentially extending supporting ring members 3^b. The parts 3^a and 3^b are adapted to removably receive and contain a plurality or series of letter-panels 4, 35 of suitable flexible material, said panels 4, being provided with suitable transparent or open letters 4^a, arranged to spell out any suitable words in the advertisements to be successively displayed within the sight-opening 1^a, and to be illuminated in proper 40 sequential order for the spelling out of the words by the mechanism hereinafter described.

As a means of intermittently driving and 45 stopping the rotary drum 3, so as to successively display the series of advertisements in the sight-opening 1^a, and holding the same in such sight-opening for the proper length of time necessary for the 50 spelling out of the words therein so displayed, one of the heads of the drum is provided with a gear 5, adapted to be intermittently driven by means of a pinion 6, mounted on a shaft 6^a, said shaft 6^a, being 55 connected to a continuously revolving driving shaft 7, through the medium of a coiled spring 8, (see Figs. 7 and 8) one end of the spring 8, being connected to the shaft 7, and the other being connected to a spring housing or hub 6^b, connected to the shaft 6^a, the 60 spring 8, and housing or hub 6^b, being enclosed or surrounded by means of a companion housing 7^a, carried on the shaft 7.

As a means of driving the shaft 7, the 65 latter is provided at one end with a worm-

wheel 9, meshing with a worm 10, carried on a shaft 11, (see Figs. 6 and 11) the shaft 11 being carried in suitable brackets 12, mounted on the stationary shaft 2, the lower end of the shaft 11, in the present instance, 70 being provided with a pulley 11^a, receiving its motion through the medium of an endless cable or belting 12^a, extending about a grooved driving wheel 13, carried upon the lower end of a motor shaft 14, the latter receiving its motion from a suitable electric motor 15, mounted, in the present instance, on one of the brackets 12. The driving shaft 7, is mounted in suitable brackets 7^b, 75 also carried upon the supporting shaft 2, and the shaft 7, is further provided with a commutator or "lamp flasher" cylinder 16, one portion of the cylinder 16, being of copper or electric conducting material and the other being of insulation curved or inclined along one edge as shown in Fig. 3, 80 of the drawings, so as to successively energize or cut into circuit the various lamps and simultaneously deenergizing or cutting out of circuit all of said lamps at suitable 85 periods of time as hereinafter explained.

As a means of intermittently driving and stopping the rotary drum at suitable intervals for the display of the advertisements in the sight-opening 1^a, of the casing, 95 and permitting the spring 8, (which is being wound up or contracted while the drum is in a stationary position) to expand and drive the pinion 6, to revolve the drum, one end of the cylinder 16, is provided with an 100 inclined notched portion 16^a, adapted to operate with a pawl or detent member 17, pivotally mounted on one of the brackets 7^b, said detent member 17, being connected to a second member 18, through the medium 105 of a loose link member 19, and a coiled contraction spring 20. The detent member 18, is connected to a supporting bracket 21, through the medium of a pivot bolt 18^a, and the detent member 18, is adapted to oscillate and alternately engage and release the stop pins 22, on the inner sides of the adjacent drum head as indicated by full and dotted lines in Fig. 9, of the drawings, 110 it being apparent that when the notched portion 16^a, of cylinder 16, comes opposite the adjacent free end of the detent member 17, the latter will snap into the notch, carrying the members 17 and 18, to the dotted line position, the free end of the lever 18, releasing the adjacent stop pin on the gear 5, the opposite end of the detent member 18, in so doing having been moved to the dotted line 115 position above the stop pin 22, at the opposite side of the gear 5, and the latter will only be permitted to move a distance corresponding to the distance between the rear end of the detent member 18, and the subjacent stop pin, and when the latter is stopped 120 beneath the detent member 18, (for a mo-

mentary period only) it will be apparent that the inclined portion of the notch 16^a, will move the members 17 and 18 to their original or full line position shown in Fig. 9, of the drawing, thereby stopping the rotary drum 3, in a position for the next line or panel or advertisement to be displayed in the sight-opening 1^a, the drum within being held in such stationary position a sufficient length of time for the spelling out of the advertisement by the successive lighting or energizing of the lamps behind each letter as hereinafter explained.

As a means of individualizing and successively illuminating each letter-panel 4, in the spelling out display of the advertisement as held at the rear of sight-opening 1^a, a stationary lamp supporting trough 23, is mounted within the casing 1, and at the rear 20 of the sight-opening 1^a, through the medium of a pair of supporting brackets 23^a, carried on a supporting shaft 2, and as a means of projecting the light from each lamp or source of illumination solely through the 25 letter of the letter-panel 4, the lamp supporting trough is provided with a series of partitions 23^b, corresponding in width of the letter-panels 4, and forming a light projecting compartment 23^c, corresponding in 30 dimensions to the letter-panels 4, adapted to individualize and project the light from the source of illumination therein solely through the adjacent registering letter-panels.

Each lamp 24, is suitably connected with 35 the commutator or "lamp flasher" cylinder 16, through the medium of suitable wires or conduits and brushes 24^a, resting upon the commutator or cylinder 16, one of each pair of wires shown leading to the base portions 40 of the brushes 24^a, being suitably insulated and connected in the circuit, and it will be apparent upon reference to Fig. 3, of the drawings that as the cylinder 16, revolves the brushes from left to right will be successively brought into contact with the conducting or circuit forming portion of the cylinder 16, thereby successively energizing from left to right the lamps 24, in the spelling out display of the particular advertisement 45 and, after the last lamp to the right is energized or cut into circuit, all of such lamps are cut out of circuit or deenergized by the brushes 24^a, coming into simultaneous contact with the insulated portion of the 50 cylinder 16.

If desired a second or standing advertisement 25, may be placed in a superposed casting or housing 1^c, and lamps 26, may be arranged to be brought into circuit or energized during the interval of the rotation of the rotary drum 3, for the display of such advertisement 25, during such interval, such lamps being intermittently energized in a manner similar to lamps 24, and in an obvious and well understood manner.

From the foregoing description, taken in connection with the accompanying drawings, the operation and advantages of my invention will be readily understood.

Having thus described one of the embodiments of my invention, what I claim and desire to secure by Letters Patent, is,—

1. In an advertising device, a casing provided with a sight-opening, light projecting compartments at the rear of said sight-opening, a rotary drum carrying letters, means for intermittently driving said drum and stopping the same with said letters between said sight-opening and light projecting compartments, and means for illuminating said compartments and letters in sequential order when the latter and said drum are in their stopped or stationary position. 75

2. In an advertising device, a casing provided with a sight-opening and carrying a series of light projecting compartments at the rear of said opening, a rotary drum carrying a series of removable letter panels, means for intermittently driving said drum and stopping the same with said letter panels between said sight-opening and light projecting compartments, electric lamps arranged in said compartments, means for successively energizing said lamps in sequential order when said letter-panels are in 90 a stationary position between said compartments and sight-opening, and means for deenergizing all of said lamps prior to and during the movement of said drum for the display of the next series of letter-panels. 100

3. In an advertising device, a casing provided with a sight-opening and carrying a series of light projecting compartments at the rear of said opening, a rotary drum having a gear wheel and carrying a series of removable letter-panels, spring resisted intermittently operated pinion mechanism meshing with said gear wheel for intermittently driving said drum, pawl and stop mechanism for releasing and stopping the same between said letter-panels between said sight-opening and light projecting compartments, electric lamps in said compartments, means for successively energizing said lamps in sequential order when said letter-panels are between said compartments and sight-opening, and means for deenergizing all of said lamps upon and during the movement of said drum for the display of the next series of letter-panels. 110

4. In an advertising device, a casing provided with a sight-opening, an intermittently driven rotatable drum therein carrying a series of lettered advertisements adapted to be successively shown through 125 said sight-opening, a series of light projecting compartments at the rear of said sight-opening and each adapted to project light through the letters in said advertisements when the letters are brought into registry 130

- 24
- with said compartments and sight-opening, a series of lamps in said compartments, means for successively cutting into circuit said lamps when said advertisements are so held in registry whereby to spell out the words in said advertisements, and means for cutting out of circuit all of said lamps prior to and during the movement of said drum for the display of the next advertisement.
- 10 5. In an advertising device, a casing provided with sight-opening, light projecting compartments therein at the rear of said sight-opening, a rotary drum carrying letters, a commutator provided with a spring connected pinion for driving said drum when released, pawl mechanism operated by said commutator for intermittently releasing said drum and stopping the same when released, with said letters in front of said 15 light projecting compartments, and means controlled by said commutator for illuminating said compartments and letters in sequential order when the latter and said drum are in their stopped position.
- 20 6. In an advertising device, a casing provided with sight-opening, light projecting compartments therein at the rear of said sight-opening, a rotary drum carrying letters, and provided with a gear wheel having 25 stop pins, a commutator provided with a spring connected pinion for intermittently driving said gear wheel and drum, pawl mechanism operated by said commutator in coöoperative relation to said stop pins for 30 stopping said drum with said letters in front of said light projecting compartments, and means controlled by said commutator for illuminating said compartments and letters in sequential order when the latter and said 35 drum are in their stopped position.
- 40 7. In an advertising device, a casing provided with a sight-opening, a stationary supporting shaft therein, an intermittently driven rotary drum thereon carrying a series 45 of removable letter-panels adapted to be successively shown in lines of advertisements
- through said sight-opening, a series of light projecting compartments carried by said shaft and adapted to project light through the letters in said advertisements when the latter are brought into registry with said compartments and sight-opening, a series of lamps in said compartments, a driving shaft provided with a spring connected pinion connected to said rotary drum, a commutator on said driving shaft for successively cutting into circuit said lamps when said advertisements are so held in registry whereby to spell out the words in said advertisement and cutting out of circuit all of said lamps prior to and during the movement of said drum for the display of the next advertisement.
8. In an advertising device, a casing provided with a sight-opening, a stationary supporting shaft therein, a rotary drum thereon carrying a series of removable letter-panels adapted to be successively shown in lines of advertisements through said sight-opening, a series of light projecting compartments carried by said shaft and adapted to project light through the letters in said advertisements when the latter are brought into registry with said compartments and sight-opening, a series of lamps in said compartments, a driving shaft operatively connected to and intermittently driving said rotary drum, and a commutator on said driving shaft for successively cutting into circuit said lamps when said advertisements are so held in registry whereby to spell out the words in said advertisement and cutting out of circuit all of said lamps prior to and during the movement of said drum for the display of the next advertisement.
- 75 85
- In testimony whereof I have affixed my signature in the presence of two witnesses.
- WADE H. BACCOCK.
